UNITED STATES PATENT OFFICE.

RUDOLPH F. STEHLIK, OF CHICAGO, ILLINOIS, ASSIGNOR TO AUTOMATIC ELECTRIC INC., OF CHICAGO, ILLINOIS, A CORPORATION OF DELAWARE.

TELEPHONE SYSTEM.

Application filed June 14, 1926. Serial No. 115,851.

The present invention relates in general to automatic telephone systems, more particularly to such systems in which line finders are employed to connect an idle trunk 5 circuit to a calling line; and the principal object, briefly stated, is the production of a new and improved finder system, in which primary line finders are directed to the contacts of a calling line, the improvement being of such a nature as to permit a reduction 10 in the cost of manufacturing and maintaining of such equipment without impairing its reliability or efficiency.

In working out an embodiment of this invention, I employ directive finders of the 15 100 point type, using switches similar to the well known Strowger connector, whose wipers are moved first in a vertical direction to select the desired level and then in a horizontal direction to select the desired contacts in that level. Switches of this type have been used for this purpose heretofore.

As a further object of my invention I provide the aforementioned finder switch with 20 a release magnet mechanism which releases the switch when the magnet deenergizes, rather than when the magnet energizes as is the common practice. In carrying out this object I use a release magnet which 25 when energized latches the so called "double dog" of the switch, and in addition actuates certain spring combinations which produce circuit changes in the finder mechanism. When the release magnet is deenergized its 30 armature withdraws the "double dog" from 35 engagement with the shaft of the switch, permitting that shaft to restore to normal in the well-known manner.

As a further object of my invention I 40 simplify the finder switch still further by employing a wiper combination which is disengaged for the bank contacts during rotation, and which is brought into engagement with the contacts of the desired line 45 after the wipers have been positioned thereon, by energizing the vertical magnet of the switch. In one embodiment of this object, I employ a four contact wiper combination on the finder, three of the wipers being spaced 50 away from the contacts during rotation, the fourth or test wiper being in engagement with the contacts over which it passes. When the desired line contacts are reached and tested for busy and found to be idle,

the vertical magnet is energized to raise the 55 shaft slightly to bring the remaining wipers of the set into engagement with the selected contact set.

As a further object of my invention I provide a new and improved sender mechanism of the retractive control type, in which the retractive control is exercised through a transformer whose primary winding is included in the circuit of the magnet to which impulses are being sent by the sender. 60 Heretofore retractive control has been accomplished by the provision of contacts operated by the magnet being controlled, those contacts sending a controlling pulse to the sender when the magnet is fully operated. 65 In accordance with this object of my invention I make use of the gradual rise of current in the magnet, by causing it to induce a current in the secondary winding of the 70 transformer, that current being employed 75 to maintain the primary circuit closed. When the magnet becomes fully energized, the current rise ceases, and the induced current dies away, permitting the sender to open the magnet circuit to end the pulse. 80

As a further object of my invention, I simplify the sender mechanism by combining the impulse counting and sequence control functions, in such a manner that they 85 may be performed by one switch which makes one half a revolution per call. One wiper set of this switch is set aside as the sequence switch, that wiper engaging first the contacts leading to the vertical magnet of the selected finder, and later to the rotary magnet of that finder, the other wipers of that switch are the ordinary impulse counting 90 wipers through which the sender is controlled to position the wipers of the finders upon the contacts of the desired calling line. 95

Further objects not specifically mentioned here, will be apparent from the reading of the detailed specification and claims which follow.

Referring now to the drawings comprising 100 Figs. 1-5, inclusive, which when arranged with Fig. 2 to the right of Fig. 1, and Fig. 3, below Fig. 1, Fig. 4, below Fig. 2, with the correspondingly numbered lines in alignment, show sufficient circuit details to enable 105 a clear understanding of one embodiment of my invention. Fig. 1 shows the usual automatic substations A and B, a finder switch

F, a secondary switch SS, and a group of relays comprising a part of the contact registration relays.

Fig. 2 shows a selector switch E controllable from a calling substation to select a trunk line, and a finder allotter FA through which the finders F are taken for use, one at a time.

Fig. 3 shows in the upper half of the sheet a group of relays comprising the remainder of the contact marking group, and on the lower half of the sheet a group of relays comprising the level marking relays, through which groups the designation of a calling line is marked in the sender.

Fig. 4 shows the sender relay group S and the sequence-counting switch SQ which jointly function to set the finders F upon the contacts of a calling line.

Fig. 5 shows the mechanical details of the finder switch F, showing particularly the structure of the back acting release mechanism.

Referring now to Fig. 1 in detail, I show two subscribers' substations A and B, whose numbers in the finder banks are 55 and 31 respectively. Fig. 1, I also show the finder F, which is mechanically similar to the well known Strowger connector, modified slightly in accordance with the objects of this invention. It will be noted that the finder F comprises only the vertical and rotary magnets 104 and 102 respectively and the release magnet 103, that is the finder contains none of the usual control relays. The release magnet mechanism of the finder F, is mechanically similar to that shown in the patent of Wilson Lee Campbell, No. 1,582,334 issued April 27, 1926, a structure in which the release armature merely engages the double-dog of the switch when the release magnet is energized, and operates a set of spring contacts to perform functions which will be apparent hereinafter. The wipers of the finder F 122 to 124 inclusive, are, with the exception of wiper 123 free from the bank contacts during the time that the rotary magnet rotates the shaft in the selected level. Wiper 123 which is the test wiper engages the line contacts for a purpose which will be apparent hereinafter. In Fig. 1, I also show a secondary switch SS which is mechanically of the well-known rotary type switch whose wipers have no normal position and move in one direction only as the switch magnet deenergizes. In the lower right hand corner of Fig. 1, I show a relay group which is a part of the contact marking relay, group through which the sender is controlled to position the finder F upon the contacts of the calling line.

In Fig. 2, I show a selector E which is the well-known Strowger selector switch, whose wipers are elevated under the control of the calling subscriber to select the desired level,

and then rotated automatically under the control of a local testing circuit to select an idle contact set in that level. In Fig. 2, I also show the finder allotter FA through which the finders F are associated with the sender equipment one at a time. Mechanically, the finder allotter FA is similar to the secondary switch SS.

Fig. 3, I show the upper portion of the figure the remainder of the contact marking relay, which together with the relays of Fig. 1 determined the contact designation of the calling line. The bottom of Fig. 3, I show the level marking relays, one of which is energized responsive to a call on one of the lines to mark the level containing that line.

In Fig. 4, I show the sender sequence switch SQ, and the sender S, through the medium of which the finders are set onto the contact of the calling line. The sender SQ is mechanically similar to the finder allotter, and contains wiper 420 which is the sequence wiper, wiper 422 which is the counting wiper, and the wiper 423 which functions to control the switch-through function of the sender S.

Referring now to Fig. 5, I show the vertical magnets 104 which attract armature 503 to engage the teeth of the hub 505, thereby lifting the wiper carrying shaft. The rotary magnet 102 actuates armature 506 to rotate the shaft. The double dog 501 engages the vertical and rotary teeth of the hub 505, to retain the shaft in its operated position. When the release magnet 103 is energized, armature 502 latches the projection of the double dog 501. When the magnet 103 deenergizes and the armature retracts, the double dog is withdrawn from the hub and the shaft restores. The operation of this mechanism is explained in more detail in the aforementioned patent of Campbell.

Throughout the drawings I have shown a plurality of batteries in order to avoid an unnecessary complication. In practice there would be but one battery, preferably with its positive pole grounded.

Assume now that the substation A, whose finder number is 55, initiates a call. The removal of the receiver will close the circuit first for the fifth level marking relay, to mark in the banks of the sender switch the fifth vertical contact so that the finder will be directed to the fifth level. After the fifth level relay is energized, the contact marking relay corresponding with the contacts of the call line, in this case, the fifth contact relay will be energized to mark the fifth rotary contact in the sender so that the finder will be directed to the fifth contact in the fifth level. This plan of energizing first the level marking relay and then the contact marking relay prevents the so called scrambling of numbers, that is the energization of the level

relay of one calling line and the contact relay of another calling line in case simultaneous calls, a combination which might direct the finder to the contacts of neither of the calling lines. The register relay arrangement of this case, is similar to that shown in my copending application Serial No. 733,471 filed August 22, 1924.

The finder allotter FA having previously 10 associated the finder F with the sender equipment S, that finder is operated as soon as the level and the contact marking relays are energized. The energization of said latter relay closes a circuit for the start 15 relay of the sender S, that relay energizing to start the impulsing. The energization of the start relay, closes a circuit from the first grounded level conductor, through wiper 422, through the impulsing relay. The impulsing relay upon energizing closes a circuit through the primary winding of transformer 402 through the wiper 420, through the vertical magnet of the finder F. Vertical magnet of the finder F is highly inductive, and the current rise therein, will 25 be gradual. During the time that the current is rising in the vertical magnet, the flux change in the core of the transformer 402, produced by the current change to the 30 primary winding, will induce in the secondary of the transformer a proportional voltage. I make use of this induced to drive current through the impulsing relay to maintain it energized, that is I connect the 35 secondary of the transformer through a locking winding of the impulsing relay. As long as the current in the vertical magnet is building up, the voltage induced in the secondary of the transformer 402 maintains the impulsing relay energized to keep the 40 vertical magnet circuit closed. As soon as the armature of the vertical magnet strikes the core, the inductance of the magnet increases appreciably, and because of this increased inductance, the current through the 45 magnet momentarily remains steady, and thereafter increases at a greatly reduced rate. Therefore as soon as the vertical magnet armature strikes the core, the secondary 50 of the transformer loses its voltage because of the momentary falling off of the rate of increase of current in the winding of the magnet. As soon as the secondary of the transformer 402 loses its voltage, the 55 impulsing relay falls back to end the impulse. Thus it will be seen I have provided the new and efficient method of revertive pulse control, by means of which a circuit is maintained closed through the winding 60 of a magnet until that magnet is fully energized. As soon as the armature of the magnet strikes the pole piece, there is nothing to be gained by maintaining the circuit closed through it, and a greater speed of 65 operation can be obtained if the circuit is

opened at the instant that the armature strikes the pole.

This interaction of the impulsing relay and the transformer in series with the magnet continues as long as the wiper 422 of the 70 counter switch finds ground, and after which the switch SQ is rotated idly until the first rotary contact is encountered. Impulsing relay and transformer again function as before, this time the transformer being in 75 series with the rotary magnet of the finder instead of the vertical. When the counting wiper 422 of the counting switch SQ loses ground, the wipers of the finder F, come to rest, and the switch SQ idles until the rotary pulsing position is reached, at which time a circuit is closed for the rotary magnet of the finder to energize that magnet to bring the wipers into engagement with the desired bank contacts. During the 80 interval in which the sender S is the transmitting impulses to the vertical and rotary magnets of the finder S, the secondary switch SS, which was started as soon as the 85 start relay of the sender was energized, has 90 been picking out an idle first selector S, to which the calling line A is connected as soon as finder wipers are brought into engagement with the selective bank contacts. As soon as SS connects with E, and F connects with the calling line, the calling subscriber hears the dial tone informing him 95 that the connection is ready for him to operate his calling device, that operation being old and well known to those skilled in the 100 art. As soon as the finder F is switched through, the finder allotter FA, is stepped off of the contacts leading to F, and is operated under the control of a local testing circuit to find the next idle finder in the 105 group. Upon a completion of the connection, ground is removed from the release ground conductor, and the finder F, selector S are restored to normal, the latter in the well known manner and the former by 110 the deenergization of the release magnet, which deenergization withdraws the pawl from engagement with the shaft. Having thus described my invention in general, I 115 will now proceed with the detailed description of its operation.

Line A calling.

When the subscriber at station A removes his receiver to initiate a call, he first completes a circuit for the fifth level marking relay 314, that circuit being traceable from ground through the normally closed springs controlled by relay 429, conductor 188, through springs 136, conductor 195, through 120 springs 120, conductor 160, through the calling device, receiver, and transmitter of the station A, conductor 161 through springs 125 121, conductor 186, through springs 358, through the normally closed contacts con- 130

trolled by spring 376, through the winding of relay 314 to grounded battery. Relay 314 energizes over this circuit and at spring 376 and its make contact locks itself to a circuit traceable from grounded conductor 188 through the winding of relay 309, through the break contact of springs 364, 367, 370, and 373, through spring 376 and its make contact, through the winding of relay 314 to 10 grounded battery. Relay 309 energizes in series with relay 314, operating springs 357 to 362 inclusive, the former to close a circuit for relays 301, 107 and 108, energizing them for purposes which will be hereinafter 15 pointed out, and the latter, that is, springs 358 to 362 inclusive, opening the circuit of other level marking relays 310 to 313 inclusive, to prevent their energization until the pending call is completed. Springs 357 20 also closes a circuit for relay 315 which energizes to operate springs 352 to 356, inclusive, to open the circuits of level relays 316 to 320, to prevent the energization of any of those level marking relays until the present 25 call is completed. The energization of relay 314 closes springs 375, thereby closing a circuit for the fifth contact marking relay 114, that circuit being traceable from ground through spring 184 and its make contact, that spring having been operated when relay 30 107 energized, through the winding of relay 114, through the normally closed contacts controlled by spring 150, through springs 141, conductor 195, through springs 120, 35 through the line conductor 160 to the calling sub-station A, through line conductor 161, springs 121, conductor 186, through resistance 308, to grounded battery, energizing relay 114. It will be noted that the relay 40 114 was short circuited by ground on conductor 188 back to the relay through springs 136, 141, and 150, until the relay 108 energized to remove that ground. This short circuiting of the contact marking relay 114 45 and the other contact marking relays, prevent the energization of any of those relays until the level marking relay has been fully energized, at which time the circuit is completed only to the level marking relays corresponding to calling ones of the line whose 50 numbers are in the level represented by the energized level marking relay. Relay 114 upon energizing locks itself over a circuit traceable from grounded spring 134 to the relay 114, spring 150 and its make contact, the break contacts of and the springs 149, 148, 147, 146, to springs 135, through the winding of relay 109 to grounded battery. Relay 109 energizes operating springs 141 to 55 145 inclusive to open the circuit of contact marking relays 110 to 113, inclusive, thereby preventing their operation at this time. At springs 151, relay 109 closes a circuit from ground through spring 151, conductor 190 through the winding of relay 302 to ground-

ed battery, energizing that relay to open the springs 336 to 340 inclusive, thereby opening the circuit of marking relays 303 to 307 inclusive, to prevent their energization at this time. With relays 314 and 114 energized, 70 the banks of the counting switch SQ of the sender are arranged so that the sender will transmit the digit 55. Ground is conducted from springs 377 and its make contact of the relay 314 through the first multiple wire to 75 the fifth contact in the lower hand of the bank over which wiper 422 sweeps. The contacts 1 to 4 of that section of the bank are also grounded from this same ground through springs 374, 371, 368, 365 and their 80 respective break contacts.

Thus the wiper 222 in traveling from contacts *f* to *g* encounters five grounded contacts *f* to *j* the remainder being ungrounded. Similarly contacts *h* to *k* of the second 85 section of the bank over which the wiper 422 sweeps are grounded from ground on spring 156 in its make contact that ground being conducted over conductor 180 to contact *h* fifth contact in that section of the bank, and the contacts between *h* and *k* are grounded through springs 155, 154, 153, 152 and their respective break contacts. Thus when the wiper 422 travels from contacts *h* to *i*, the first five will be grounded, and the second five 95 open circuited. The energization of relay 302 closes at springs 341 of its make contact a circuit for the start relay 407 of the sender equipment, that circuit being traceable over the conductor 321 through spring 430 100 through the winding of the relay to grounded battery. Relay 407 upon energizing starts the sending mechanism through its cycle of operation upon the contacts of the calling line.

Returning now to the energization of relay 107, which closes at springs 133 a circuit traceable over conductor 187 through the winding of slow to pull up relay 404 to 105 grounded battery. Relay 404, delays in operating sufficiently long to permit start relay 407 to energize first. When relay 404 energizes, it operates springs 429, to remove the permanent ground from conductor 188 and to substitute therefor ground through 110 spring 435 and its make contact, through spring 429 and its make contact to the conductor 188. The springs 435 being controlled by the relay 407, can subsequently remove ground from conductor 188, to permit 115 the release of relays locked thereto.

Vertical impulsing.

Energization of relay 407 closes a circuit from ground on spring 377 and its make 125 contact through the break contacts of springs, 374, 371, 368, and 365, to the first conductor in the vertical bank over which wiper 422 sweeps, through wiper 422, to springs 424, conductor 452, springs 457, 130

through the upper winding of relay 403. Relay 403 energizes and at springs 426 closes a circuit for the vertical magnet of the finder F, traceable from ground through springs 426, through the upper winding of the transformer 402, conductor 450, wiper 421, now engaging contact *a*, conductor 250, wiper 233 of the finder allotter FA, conductor 173, through the winding of vertical magnet 104 of the finder F to grounded battery. The vertical magnet energizes over this circuit elevating the shaft and wipers of the finder F, one step. During the interval that the current is rising in the vertical magnet, the voltage induced in the secondary winding of transformer 402, holds relay 403 energized over the circuit including springs 427 and the lower windings of transformer 402 and the relay 403. Energization of relay 403 closes a circuit from ground through wiper 423 and the first bank contact it engages, conductor 454, springs 438, springs 428 and its make contact, through the winding of magnet 401 of the sequence switch SQ, to grounded battery, energizing that magnet preparatory to advancing the wipers 420 to 423 inclusive, and to open at springs 424 the circuit just traced through the upper winding of relay 403. When the vertical magnet is fully energized, there will be no current change to the primary winding of the transformer 402 and consequently the locking circuit just traced for the relay 403 will be without voltage, and since the initial energizing circuit of that relay is open at spring 424, relay deenergizes to end the pulse. When relay 403 deenergizes it opens the circuit of the vertical magnet, permitting that magnet to fall back preparatory to taking another step. Relay 403 also opens a circuit of the magnet 401, which deenergizes and advances the wipers of the switch SQ one step, that is to the second bank contact. The circuit for the upper winding of relay 403 is now closed through the second contact engaged by wiper 422 from ground on spring 377 and its make contact, through spring 368 and its break contact, that relay energizing to transmit another pulse to the vertical magnet. The operation as just described continues to five impulses at which time the wipers of the finder F are standing opposite the fifth level of their bank and at the end of which wiper 422 is engaging the sixth bank contact in the vertical section of its bank, that is the contact *j*. Since relay 314 is energized, spring 377 is against its make contact and contact *j* is ungrounded as are the remaining contacts between *j* and *g*. The circuit of relay 403 is therefore not closed and the vertical magnet receives no further impulses. A circuit may now be traced from ground through wiper 423 now engaging the sixth bank contact which is multiplied to the con-

ductor 454, springs 438, spring 428 and its break contact, springs 425, through the winding of magnet 401 to battery, energizing that magnet which breaks its own circuit at the springs 425, deenergizing the magnet and permitting the armature to fall back to advance the wiper 420 to 423 inclusive one step. When the armature of magnet 401 restores, the circuit just traced through the magnet is again closed at springs 425, whereupon the magnet reenergizes and again interrupts its own circuit, in a buzzer like manner to advance the switch wipers. This operation continues until wiper 422 engages contact *h* at which time wiper 420 has passed the contacts to which vertical impulsing conductor 250 is multiplied and is engaging the contact *c* to which the rotary impulsing conductor 251 is multiplied, and the sender mechanism is in position to transmit the rotary impulses to the finder.

Rotary impulsing.

With the wiper 422 engaging contact *h*, the circuit is again closed for the upper winding of the relay 403, that circuit being traceable from ground spring 156 and its make contact through the break contacts of springs 152, to 155, inclusive, the first rotary counting conductor 184, which is connected to the contact *h*, through the wiper 422, springs 424, conductor 452, springs 437, to the upper winding of relay 403 to battery. Relay 403 energizes closing at its springs 426 a circuit for the rotary magnet of the finder F, traceable from that spring through the upper winding of transformer 402, conductor 450, wiper 420, now engaging contact *c*, conductor 251, wiper 237 of the finder allotter FA, conductor 171, through the winding of rotary magnet 102, to grounded battery, energizing that magnet to advance the wipers of the finder F one rotary step. During the time the current is building up in the rotary magnet, the current change through the primary winding of the transformer 402 induces a current in the secondary winding, that current being effective to hold relay 403 energized as before. Relay 403 again closes a circuit through spring 428 and its make contact for the winding of the magnet 401 of the counting switch SQ. When the magnet 402 of the finder F is fully energized relay 403 deenergizes permitting the magnet 102 to fall back preparatory to taking another step, and permitting the magnet 401 to fall back to advance the wipers 420 to 423 one step. Since contacts *h* to *k* by wiper 422 are all grounded, the above traced circuit to rotary magnet 102 will be closed while the wiper is passing over those contacts, that is the rotary magnet will receive five impulses, and will function to position the wipers of the finder F opposite the test contact in the level, in

this case the fifth contact in the fifth level. When magnet 401 deenergizes after the fifth impulse, wiper 422 moves from contact *h* to the next contact, that contact and the remaining contacts between it and the contact *i* are ungrounded, so that the circuit for relay 403 will not be again closed and no more impulses will be transmitted to the rotary magnet. The local circuit for magnet 401 which has been traced from wiper 423 then the springs 425, will again be closed and the magnet will operate in a buzzer like fashion to advance the wipers until the wiper 423 reaches the contact *e* of its bank at which time the switch-through function take place, provided the secondary switch is in the proper position.

Secondary switch searches for idle selector.

20 Returning now to the energization of relay 407, a circuit may be traced from ground through springs 434, through the upper winding of relay 408, conductor 255, through wiper 241 of the finder allotter FA, conductor 178, through the rotary magnet 105 of the secondary switch SS, through the interrupter 194 to grounded battery. If the wipers 128 to 130, of the secondary switch SS, are standing on the contacts of a busy 25 trunk line, wiper 129 will encounter a grounded contact, closing a short circuiting path for the upper winding of relay 408, that circuit being traceable from grounded wiper 129, conductor 177, wiper 238 of the switch FA, conductor 252, springs 433, spring 440 and its break contact, to the upper winding of relay 408. The upper winding of relay 408 is thus short circuited and since direct ground is supplied to the magnet 105 over the circuit just traced that magnet will energize when the interrupter 194 closes the circuit to battery. When the interrupter opens the battery circuit, magnet 105 deenergizes and advances the wipers 30 128 to 130 one step. This operation continues as long as wiper 129 encounters grounded contacts. Assuming that the switch E is idle, conductor 175 will not be grounded and when the wiper 129 encounters 35 the contacts of which the conductor 175 is connected, the short circuit will be removed from the upper winding of relay 408 and that relay will energize in series with the magnet 105 when the interrupter 194 again 40 closes the battery circuit. Because of the resistance of the upper winding of relay 408, the magnet 105 does not energize this circuit. Relay 408 upon energizing, locks itself over a circuit traceable from ground 45 to spring 435 and its make contact, springs 441, through the lower winding of relay 408 to grounded battery. The energization of relay 408, at springs 440, prepares a point in the switch through circuit, the circuit 50 being held open at this time by springs 443

of the relay 409. At springs 439, relay 408 closes a circuit from ground through those springs and conductor 253, wiper 239, conductor 172, through the winding of release magnet 103 of the finder F, energizing that magnet which latches the double dog of the switch, (not shown), preparatory to releasing it. The magnet 103 upon energizing closes a circuit through resistance 158, springs 125, conductor 177, the wiper 129 of the secondary switch SS, the ground on conductor 172 traversing that circuit to mark the selector E as busy. The energization of release magnet 103 also closes a circuit of the grounding conductor 172 through resistance 158, springs 125, resistance 157, springs 127, through the winding of the vertical magnet 104 to battery, but owing to the high value of resistances 157 and 158 in series, the ground on conductor 172 has negligible effect upon vertical magnet 104, should that magnet be operating at this time. Thus it will be seen that the energization of relay 408, responsive to the finding of an idle selector by the secondary switch SS prepares the finder and control equipment for the switch through operation, that operation being performed at the time that the sequence switch SQ places its wiper 423 upon the contacts *e*. 95

Switch through.

When wiper 423 reaches contact *e*, a circuit may be traced from ground, through wiper 423, conductor 453, through winding of relay 409, through resistance 442 to grounded battery, energizing that relay to switch through the finder, unless the test wiper of the finder has encountered a grounded contact, indicating that the calling line has been called by a connector prior to the arrival of the finder wipers on its contacts. Relay 409 upon energizing closes a circuit from ground through springs 443, springs 440, springs 433, conductor 252, wiper 238, conductor 177, through resistance 157, springs 127, through the winding of vertical magnet 104, to battery, energizing that magnet to elevate the shaft sufficiently to bring wipers 122, 123' and 124 into engagement with contacts 146 to 166, respectively. The elevation of wiper 123' into engagement with contact 165 closes a circuit from ground through that wiper and contacts, through the winding of relay 101 to grounded battery, energizing that relay. At springs 120 and 121, relay 101 opens the register relay circuits, permitting the registers to restore in the manner subsequently pointed out. This operation of relay 101 100 clears the calling line attachments. The grounding of contact 165 by wiper 123' protects the calling line from intrusion by a connector, the grounded private normal *p* rendering it busy to connectors in the well known 105 110 115 120 125 130

manner. The calling line A is now connected through to the first selector E over circuit traceable from ground through transformer winding 210, through the lower winding of relay 201, springs 232, conductor 176, wiper 130, wiper 124, engaging contacts 166, line conductor 161, through the telephone to line conductor 160, contact 164, wiper 122, wiper 128, conductor 174, springs 228, through the upper winding of the line relay 201 to grounded battery. The subscriber is apprised of the fact that he has obtained a first selector by dial-tone superposed on the above circuit through the winding 210 of the dial-tone transformer, that tone informing them that the equipment at the central station is in readiness to receive his directive impulses, and he proceeds to operate his calling device to set up the connection he desires. The operation of the selector E responsive to the actuation of the subscribers calling device is well known to those skilled in the art and need not be repeated in detail here, it being sufficient to say that the first series of impulses dialed by the subscriber operate the vertical magnet 206 of the selector to the level that is determined by the number of impulses in the digit. The selector then rotates automatically being driven by the rotary magnet 208, coming to rest upon the first idle contact in that level, at which time the switch through relay 205 energizes and extends the trunk line to the next switch, which may be either another similar selector or a connector, depending upon the size of the exchange.

Sender S restores to normal and finder allotter FA seeks idle finder.

At the time that the circuit was closed through wiper 423 to the relay 409, a parallel circuit was closed from conductor 453, through spring 436 and its make contact, thence over two parallel paths the one through the upper winding of relay 408 and grounded battery, and the other over conductor 257 through the winding of magnet 209, of the allotter FA, to grounded battery, energizing the relay and the magnet. Relay 405 upon energizing opens, at springs 430, a point in the circuit of start relay 407, permitting that relay to fall back after a slight interval. The energization of magnet 209 attracts the armature preparatory to advancing the wipers 236 to 241 inclusive of the allotter FA onto the next bank contact. When relay 407 falls back, it closes its circuit from grounded conductor 453, through spring 436 and its break contact, springs 425, winding of magnet 401 to grounded battery, energizing this magnet, which interrupts its own circuit of springs 125 and falls back to advance the wipers 420 to 423 into their normal position, as shown in the

drawing. The deenergization of relay 407 disconnects ground from conductor 177 of the finder F at springs 433, that disconnection of ground being without effect at the time, since the release relay 202 of the selector E, 70 has energized, and at spring 221 grounded the conductor 175, which is connected to conductor through wiper 129. The energization of relay 407 removes ground from conductor 188 at springs 435, releasing energized relays 309, 314, which were locked thereto, those relays upon deenergizing in turn unlock relays 114, 107, 301 and 315, thereby restoring the register mechanism to normal in readiness for the next call. The deenergization of relay 407 at springs 431 close the local testing circuit for finder allotter FA. When the magnet 209 has deenergized and advanced the wipers 236 and 241 to the next bank contact, wiper 240 encounters a 85 grounded contact if that finder was busy, closing a circuit from that ground to conductor 254, springs 434, conductor 256, springs 242, through the winding of magnet 209 to grounded battery. Magnet 209 energizes over the circuit and at springs 242 interrupts its own circuit falling back to advance the wipers another step. Magnet 209 operates in a buzzer like manner as long as the wiper 240 encounters grounded contacts, coming to rest deenergized upon the first ungrounded contact, thereby associating the idle finder with the sender mechanism. 95

All finders busy.

As was mentioned above the energization of release magnet 103 of the finder F of springs 126 moves ground from the conductor 179, that conductor, being the all finders busy conductor, is multiplied to all of the finders in the group and if there is another idle finder in the group this removal of ground by magnet 103 without effect at this time. However, if the finder F is 105 the last idle finder of the group, springs 126 upon removing ground from the conductor 179, removes the normal short circuit from the lower winding of relay 407, and permits that relay to energize as 110 soon as relay 407 deenergizes, over a circuit traceable from ground through spring 435 and its break contact, through the lower winding of relay 405 to resistance 406 to grounded battery. Relay 405 upon energizing opens at springs 430 a point in the circuit of start relay 407, thereby preventing that start relay from energizing until the finder allotter FA has connected with an 115 idle finder. It will be noted that if the all finders of the group are busy, the finder allotter wiper 240 will not engage an ungrounded contact, and as a result the finder allotter will rotate continuously until one 120 finder in the group becomes idle, at which 125 130

time that finder will be seized by the finder allotter.

Connector called line A before F connects with it.

It will be noted that the contacts of the connector bank associated with the line A are not protected by the initiation of the call on that line until the finder such as F connects with it and grounds the contact 165 through the wiper 123'. It may happen that during the interval between the removal of the receiver from this substation A and the connection of the finder F to that line, that a connector may extend a call to the station over the normal cables. The connector will immediately ground the private which is connected to the contact 165, and energize relay 101 to operate springs 120 and 121 to remove the attachments from the line so that the connector may ring thereon. Opening springs 120 and 121 at this time will not effect the sender S from directing the finder F to the contacts of the calling line, since the registration relays are already energized, and locked up independent of the loop circuit. The finder F arrives on the line A, this ground on contact 165 will traverse the circuit through wiper 123, conductor 170, wiper 240 of the finder allotter FA, conductor 254, spring 231 and its make contact, through the resistance 442 to grounded battery, short circuiting the relay 409, so that when the sequence switch SQ positions wiper 423 and the contact e, preparatory to switching through, relay 409 will not energize, and the finder F will not be switched through. The ground on conductor 453 however, will energize the relay 405, to release the sender S and to cause the finder allotter FA to seek another finder. When the finder allotter FA, moves wipers 238 off the contact to which conductor 177 is connected, and moves wiper 239 off the contact of which conductor 172 is connected, the energizing and locking circuits of the release magnet 103 of the finder F are broken, permitting that magnet to deenergize and withdraw the double-dog from the shaft, whereupon the finder F restores to normal in the usual manner. The sender S restores to normal, the sequence switch advances its wipers to their normal position, and the finder allotter associates the sender S with the next idle finder of the group, and the equipment is in readiness for handling the next call.

Release.

After the subscriber has operated the first selector as indicated above, and extended the connection to the connector, that switch maintains ground upon the release trunk conductor 175, which through wiper 129 and conductor 177 marks the finder F busy to

the finder allotter FA, and maintains the vertical magnet 104 and the release magnet 103 energized. When the conversation has been completed, and the subscribers replace their receivers, the connector removes ground from the conductor 175, whereupon the vertical magnet 104 deenergizes, and the release magnet 103 deenergizes, the latter withdrawing the double-dog from the shaft permitting it to restore to normal. Ground is removed from the contact 165, whereupon relay 101 restores to normal closing a circuit to springs 121 and 120 and their respective break contacts, so that the line is in its normal position and can register another call in the finder register groups.

The foregoing description of one embodiment of my invention is made by way of example only, using a particular type of equipment. I do not wish to be limited by the specific disclosure as there are many modifications and adaptations which can be made by one skilled in the art without departing from the scope of the invention.

Having thus described my invention, what I consider new and desire to have protected by Letters Patent, is pointed out in the appended claims.

What is claimed is:

1. In a telephone system, a finder switch having wipers and banks of contacts through which connections are established, only one of said wipers engaging associated contacts while it is in motion, subscriber's lines terminating in said banks, means for extending connections to said lines, means responsive to the initiation of a call on one of said lines for positioning said finder wipers opposite the contacts of said calling line, and means for preventing the establishment of a connection between said wipers and contacts and for releasing said operated finder if a connection has been established to said line during the interval between the initiation of said call and the positioning of said wipers.

2. In a telephone system, a finder switch having wipers and banks of contacts through which connections are established, only one of said wipers engaging associated contacts while it is in motion, subscribers' lines terminating in said banks, means for extending connections to said lines, means responsive to the initiation of a call on one of said lines for positioning said finder wipers opposite the contacts of said calling line, means for preventing the establishment of a connection between said wipers and contacts and for releasing said operated finder if a connection has been established to said line during the interval between the initiation of said call and the positioning of said wipers,

and means for establishing a connection between said wipers and contacts if no prior connection has been established.

3. In a telephone system, a group of finder

switches each having wipers, said finders containing only the magnets for positioning said wipers to establish a connection, and means common to said group for controlling the operation of said magnets, first to position said wipers and subsequently to establish a connection through said wipers.

4. In a telephone system, a finder switch having wipers, switch banks containing contacts through which said wipers establish connections, subscribers' lines terminating in said bank contacts, primary and secondary magnets in said finders, means responsive to a call on one of said lines to operate said magnets to move said wipers in a primary and a secondary direction respectively to position them before the contacts of said calling line, and means for then energizing said primary magnet to bring said wipers into engagement with said contacts.

5. In a telephone system, a finder switch having wipers, switch banks containing contacts through which said wipers establish connections, subscribers' lines terminating in said bank contacts, primary and secondary magnets in said finders, means responsive to a call on one of said lines to operate said magnets to move said wipers in a primary and a secondary direction respectively to position them before the contacts of said calling line, certain of said wipers engaging selected ones of said contacts and the remaining wipers being spaced away from the respective contacts, and means for then energizing said primary magnet to bring said remaining wipers into engagement with said contacts.

6. In a telephone system, a finder switch having wipers, switch banks containing contacts through which said wipers establish connections, subscribers' lines terminating in said bank contacts, primary and secondary magnets in said finders, means responsive to a call on one of said lines to operate said magnets to move said wipers in a primary and a secondary direction respectively to position them before the contacts of said calling line, certain of said wipers engaging selected ones of said contacts and the remaining wipers being spaced away from the respective contacts, and means for then energizing said primary magnet to bring said latter wipers into engagement with the respective contacts while maintaining the connection between said former wipers and contacts.

7. In a telephone system, a finder having wipers, primary and secondary magnets for positioning said wipers, subscribers' lines terminating in contacts available to said wipers, a sender and a sequence switch for controlling it, means responsive to the initiation of a call on one of said lines for operating said sender and sequence switch to position said wipers before the contacts

of the calling line, a secondary switch operable to connect said finder with an idle trunk line, means controlled by said sender for operating said secondary switch simultaneously with said finder and until it connects with an idle trunk, means responsive to a further operation of said sequence switch after said wipers are positioned for preparing a switching circuit through which said finder is brought into connection with said line, means for preventing the operation of said switching means if said secondary switch has not connected with a trunk.

8. In a telephone system, a finder having wipers, primary and secondary magnets for positioning said wipers, subscribers' lines terminating in contacts available to said wipers, a sender and a sequence switch for controlling it, means responsive to the initiation of a call on one of said lines for operating said sender and sequence switch to position said wipers before the contacts of the calling line, a secondary switch operable to connect said finder with an idle trunk line, means controlled by said sender for operating said secondary switch simultaneously with said finder and until it connects with an idle trunk, and means for operating said switching means and for releasing said sender and sequence switch when said secondary switch connects with said trunk line.

9. In a telephone system, a finder having wipers, primary and secondary magnets for positioning said wipers, subscribers' lines terminating in contacts available to said wipers, a sender and a sequence switch for controlling it, means responsive to the initiation of a call on one of said lines for operating said sender and sequence switch to position said wipers before the contacts of the calling line, a secondary switch operable to connect said finder with an idle trunk line, means controlled by said sender for operating said secondary switch simultaneously with said finder and until it connects with an idle trunk, means responsive to a further operation of said sequence switch after said wipers are positioned for preparing a switching circuit through which said finder is brought into connection with said line, means for preventing the operation of said switching means and for releasing said finder, sender and sequence switch after a definite interval if said secondary switch does not meanwhile connect with a trunk.

10. In a telephone system, a finder having wipers, primary and secondary magnets for positioning said wipers, subscribers' lines terminating in contacts available to said wipers, a sender and a sequence switch for controlling it, means responsive to the initiation of a call on one of said lines for operating said sender and sequence switch to position said wipers before the contacts of the calling line, a secondary switch operable to

- connect said finder with an idle trunk line, means controlled by said sender for operating said secondary switch simultaneously with said finder and until it connects with an idle trunk, a switching relay in said sender, means for preventing the energizing of said relay until said secondary switch has connected with a trunk, and means responsive to a further operation of said sequence switch after said wipers have been positioned for closing an operating circuit to said switching relay and to a releasing means, said switching means operating to operate said wipers into connection with said contacts if said secondary switch has connected with a trunk and said releasing means operating independent of said switching relay to release said equipment after a definite interval.
11. In a telephone system, a finder having wipers, a secondary switch having wipers, contacts in said switches through which said wipers establish connections, said finder wipers disengaging said contacts when in motion and said secondary wipers normally engaging its contacts, a direct connected link between the wipers of said switches, subscribers' lines terminating in said finder switch contacts, trunk lines terminating in said secondary switch contacts, means responsive to a call on one of said lines for positioning said finder wipers opposite the contacts of that line and for simultaneously starting said secondary switch in search of an idle one of said trunk lines, and means operated after said wipers are positioned to bring them into engagement with the selected contacts only if said secondary switch has connected with an idle trunk line.
12. In a telephone system, a finder switch having wipers, switch banks containing contacts through which said wipers establish connections, subscribers' lines terminating in said bank contacts, primary and secondary magnets in said finder operative to move said wipers in a primary and a secondary direction respectively, a release magnet in said finder, a detent for retaining said wipers in the position in which they were last set, an armature for said release magnet, operated to engage said detent when said magnet energizes and to withdraw said detent to release said wipers when said magnet deenergizes, means responsive to a call on one of said lines for operating said primary and secondary magnets to position said wipers before the contacts of that line, means for then energizing said release magnet, means controlled thereby for energizing said primary magnet to bring said wipers into engagement with said contacts, and means for subsequently deenergizing said release magnet to restore said finder to its normal position.
13. A sender mechanism comprising

means for closing a circuit through one winding of a control transformer and a magnet in series, and means controlled by said transformer for maintaining said circuit closed while the current flow in said circuit is increasing and for then opening it.

14. A sending mechanism, a magnet controlled thereby, a relay and a transformer in said mechanism, a circuit for one winding of said transformer and magnet in series controlled by said relay, a holding circuit for said relay energized by current induced in the secondary winding of said transformer by the current rise in said primary winding, an armature for said magnet attracted thereto when the magnet is energized, said current rise being arrested when said armature strikes the magnet and said induced voltage being then eliminated to release said relay to open said first circuit.

15. A sending mechanism containing a transformer having two windings a magnet, means in said sender operated to a circuit through one winding of said transformer and said magnet, and transformer controlled means for maintaining said first means operated until said magnet becomes fully energized.

16. In a telephone, a sending mechanism, means for registering a number therein, an impulsing device in said sender, a plurality of magnets, operable by said device, a counting switch in said mechanism containing a wiper through which said device is controlled in accordance with the digits of said registered number, and means comprising a second wiper of said switch for connecting said device to said magnets in the proper sequence.

17. A sending mechanism comprising a pulsing relay, a transformer having two windings, means for energizing said pulsing relay, a magnet and a circuit therefor completed by means controlled by said pulsing relay, one winding of said transformer included in said circuit in series with said magnet, the current in said circuit rising to its maximum value at a rate governed by the inductance of said circuit, a locking circuit for said relay closed through the second winding of said transformer and energized by the current induced therein by the current rise in said primary winding, said second winding being deenergized to release said relay open said circuits when said magnet becomes energized fully.

18. A sending mechanism, a magnet controlled thereby, means in said sending mechanism for closing a circuit to said magnet, and means controlled by said magnet over said circuit for opening said circuit.

19. A sending mechanism, a source of current, a magnet, means in said sending mechanism for closing a circuit from said source of current to said magnet, and means con-

trolled by the rise of current in said magnet for maintaining said circuit closed.

20. A sending mechanism, a source of current, a magnet, means in said sending mechanism for closing a circuit from said source of current to said magnet, and means in said circuit controlled by the current flow in said magnet for first maintaining and then opening said circuit.

10 21. A sending mechanism, a source of cur-

rent, a magnet, a relay in said sending mechanism, means for operating said relay to close a circuit from said source of current to said magnet, and means controlled by the rise of current in said magnet for holding¹⁵ said relay energized to maintain said circuit closed.

In witness whereof, I hereunto subscribe my name this 11th day of June, A. D., 1926.

RUDOLPH F. STEHLIK.
